UNITED STATES PATENT OFFICE

109,849

DESIGN FOR A COMBINATION FUR AND FABRIC WHIPPING APPARATUS

Charles M. McCarthy, Minneapolis, Minn.

Application January 21, 1938, Serial No. 74,458

Term of patent 14 years

To all whom it may concern:

Be it known that I, Charles M. McCarthy, a citizen of the United States, residing at 2112 Blaisdell Avenue, Minneapolis, county of Hennepin, and State of Minnesota, have invented a new, original, and ornamental Design for a Combination Fur and Fabric Whipping Apparatus, of which the following is a specification, reference being had to the accompanying drawing, forming part thereof.

Fig. 1 is a side elevational view of a combination fur and fabric whipping apparatus showing

my new design with four straps broken away for convenience of illustration;

Fig. 2 is a rear elevational view thereof; and

Fig. 3 is a top plan view thereof, with the strap and shaft portions omitted for convenience of illustration.

I claim:

The ornamental design for a combination fur and fabric whipping apparatus, as shown and described.

CHARLES M. McCARTHY.
